UNITED STATES PATENT OFFICE.

EDWIN NORTON, OF NEW YORK, N. Y.

CONTINUOUS HEATING-FURNACE.

No. 874,422.

Specification of Letters Patent.

Patented Dec. 24, 1907.

Application filed February 27, 1907. Serial No. 359,589.

To all whom it may concern:

Be it known that I, EDWIN NORTON, a citizen of the United States, residing at New York, county and State of New York, have 5 invented or discovered new and useful Improvements in Continuous Heating-Furnaces, of which the following is a specification.

My invention relates to heating furnaces 10 designed especially for the heating of packs of metal sheets preparatory to a rolling operation thereon, but it is also applicable to the heating of single sheets, bars, rods, etc.

It is the object of the present invention to 15 improve that type of continuous furnaces, which employ screw-threaded means for feeding through the furnace packs or sheets edgewise in the threads.

A further object is to provide suitable 20 mechanical means for introducing the packs or sheets into the furnace and depositing them between the threads, and to provide suitable means for removing the pack or sheets from the furnace after they have been suitably 25 heated.

Referring to the drawings, Figure 1 is a horizontal section at the level of the conveyer screws; Fig. 2 is a section on the line 2—2 of Fig. 1; Fig. 3 is a section on the line 30 3—3 of Fig. 2; Fig. 4 is a detail partly in section and partly broken away, showing an elevation of the blank charging mechanism; and Fig. 5 is a vertical section through one of the forks of the said charging mechanism.

35 On the drawings, 1 represents a furnace chamber, having therein the two horizontal screws 2 and 3 journaled preferably in the front and rear walls of the furnace. The screws converge toward the rear end of the 40 furnace, their convergence, or inclination toward each other, is preferably such that the packs represented by the numerals 4 and 5 will stand edgewise between opposite pairs of threads without binding on the thread- 45 walls or becoming wedged between the same; that is, the corresponding or opposite threads on the two screws include substantially parallel planes, all substantially at right angles to an imaginary line extending 50 longitudinally of the furnace midway between the screws. The described inclination of the screws also prevents the distortion or curvature of blanks to make them sit between the threads.

55 At the front end of the furnace the screws are provided with the worm-wheels 6 geared

to the worms 7 on the shaft 8, the latter being driven through the gear-wheels 9 by the motor 10. Each of said screws has an axial opening 11, closed at the rear end by the 60 screw-plug 12. The front end of each opening 10 is closed by a hollow stationary bearing 13, fitting water-tight within the outer end of a hollow extension 14 secured to the front end of the screw. A pipe 15 extends from 65 the rear end of the opening in each screw out through the cap of the bearing 13, the two pipes being connected together by the hollow valve fitting 16, provided with the valve operating wheel 17. Each bearing has an outlet 18.

19 is an inlet pipe connected to the fitting 16.

The screws can be cooled by passing a cooling fluid through the inlet pipe 19, the fitting 16, the pipes 15, and the openings in the rear ends thereof into contact with the bodies of the screws, whence it passes forward and out through the outlet pipes 18. During the rotation of the screws the extensions 14 rotate fluid-tight on the hollow bearings 13.

In the roof of the furnace near the ends thereof are the blank entrance and discharge openings 20 and 21, respectively, extending transversely of the furnace and parallel with 85 the planes included within corresponding opposite threads of the screws. The openings 20 and 21 are closed by the swinging doors 22 and 23, each held normally closed, by the weights 24 on the arms 25 secured to the 90 rocking pivots 26 to which the doors are attached.

Beneath the opening 20 and in line therewith are the two plunger tubes 27 reciprocable through the floor of the furnace and carrying at their upper ends the hollow forks 28, between the members of which the packs of sheets may be supported on edge, as shown in Fig. 2. The plungers 27 are secured at their lower ends in the horizontal tube 29, 100 supported on the plunger of the hydraulic cylinder 30.

31 represents a water inlet pipe which extends through the pipes 29 and 27 and nearly to the tips of the hollow fingers 28. The 105 water escapes through the outlet pipe 32 connected to the pipe 29.

The rear end of the furnace is provided with hydraulic pack-supporting mechanism like that indicated by the numerals 27 to 30, 110 the corresponding parts bearing the same numerals with prime (') marks.

The operation of my invention is as follows: The furnace having been brought up to the proper heat, the pressure is admitted to the hydraulic cylinder 30 and the forks 28 are thrust up through the opening 20, the ends of the forks pushing the door 22 open. A pack of sheets is then deposited by an overhead traveling crane or otherwise between the members of the forks 28. The motor 10 having been started, the cylinder 30 is exhausted and the forks lower the pack into the furnace and deposit the same on the screws 2 and 3, between whose threads it will at once or very soon 5 on a slight rotation of the screws be seated. The forks retire below the lower edge of the pack. As soon as the pack is clear of the path of the forks, the latter are caused to ascend and receive another pack, which is deposited between the 10 screw threads in the same manner as before. This process is repeated as desired. As the screws rotate (preferably in opposite directions to keep the packs from endwise movement) the packs move gradually on edge to 15 the rear end of the furnace, receiving heat during their travel. When each pack arrives opposite the opening 21, the cylinder 30' is actuated and the pack is seized by the forks 28' and lifted up through the said opening, automatically lifting the door 23. The 20 heated pack is then carried by any suitable mechanism to a rolling mill where the gage of the sheets is reduced and the length thereof correspondingly increased. The weights 25 24 automatically close the doors 22 and 23 when not obstructed by the packs or the forks.

I believe I am the first to devise a continuous furnace wherein packs or sheets may be 30 received and supported edgewise between thread walls and caused to travel in the furnace.

I have made the threads of the screws sufficiently deep to enable them alone to maintain 35 the packs or sheets on edge. The screws, as they rotate, remove the portions thereof cooled by contact with the sheets and substitute therefor hot portions which transfer their heat to the plates, so that the portion of 40 the sheets between the threads will be heated substantially the same degree as the remaining portions. It is not necessary with screws made of steel to have them water cooled.

I do not limit my invention to any definite 45 number of screws since even the use of one screw with suitable pack supporting devices would come within the invention as claimed.

1. In a continuous furnace, a pair of oppositely arranged screws extending longitudinally 50 within the furnace chamber, means for mounting the screws with their axes inclined

one toward the other, and means for rotating the screws, whereby blanks may be supported between the corresponding threads of the screws and conveyed longitudinally of 55 the furnace without binding on the threads or distorting the blanks.

2. In a continuous furnace for heating 60 packs or sheets on edge, a rotary screw in the chamber of the furnace for supporting and conveying the packs or sheets, the threads of said screw having such depth that the thread walls maintain said packs or sheets on edge.

3. In a continuous furnace for heating 65 packs or sheets on edge, a pair of oppositely arranged rotary screws in the furnace chamber for supporting and conveying packs or sheets, the threads of said screws having such depth that the thread-walls maintain said 70 packs or sheets on edge.

4. In a continuous furnace, having an opening in the roof thereof, a blank transferring device reciprocable in the furnace chamber and through the said opening. 75

5. In a continuous furnace, a rotatable screw located within the furnace chamber and adapted to receive blanks in its threads, a reciprocable blank carrier having means for receiving blanks and means for moving 80 the carrier with a contained blank transversely of the screw, whereby a blank may be delivered to said screw or removed therefrom.

6. In a continuous furnace, a rotatable 85 screw located within the furnace chamber and adapted to receive and convey flat blanks on edge in its threads, and a reciprocable blank carrier adapted to receive said blanks on edge and convey them on edge to 90 the threads of said screw.

7. In a continuous furnace, a rotatable screw located within the furnace chamber and adapted to receive and convey blanks in its threads, and a reciprocable blank carrier, having means for transferring blanks from said screw and discharging them from the said chamber. 105

8. In a continuous furnace, a rotatable screw located within the furnace chamber and adapted to receive and convey flat blanks on edge in its threads, and a reciprocable blank discharging device adapted to receive the blanks from said screw and discharge them on edge from said chamber. 110

Signed at Pittsburg, Pa., this 2nd day of January, A. D. 1907.

EDWIN NORTON.
